AEROSPACE VEHICLE OR SIMILAR ARTICLE

Burton Barnett, Los Alamitos, Frederick Raymes,
Los Angeles, and Thomas Sackinger, Hacienda
Heights, Calif., assignors to North American
Rockwell Corporation

Filed Nov. 13, 1967, Ser. No. 9,355

Term of patent 14 years

U.S. Cl. D71—1
Int. Cl. D12—07

FIG. 1

FIG. 4

FIG. 2

FIG. 3

FIG. 5

FIG. 7

FIG. 6

FIG. 8

FIG. 1 is a perspective view of an aerospace vehicle or similar article showing our new design with its movable wings in a retracted position;

FIG. 2 is a side elevational view of one of the two substantially identical sides of the aerospace vehicle or similar article of FIG. 1;

FIG. 3 is a top elevational view of the aerospace vehicle or similar article of FIG. 1;

FIG. 4 is a rear elevational view of the aerospace vehicle or similar article of FIG. 1;

FIG. 5 is a perspective view of the aerospace vehicle or similar article of FIG. 1 with its movable wings extended laterally from the body thereof;

FIG. 6 is a side elevational view of one of the two substantially identical sides of the aerospace vehicle or similar article of FIG. 5;

FIG. 7 is a rear elevational view of the aerospace vehicle or similar article of FIG. 5 with the wings extended; and

FIG. 8 is a top elevational view of the aerospace vehicle or similar article of FIG. 5 with the movable wings extended.

We claim:

The ornamental design for an aerospace vehicle or similar article, as shown and described.
